(57) **CLAIM**

The ornamental design for a fluid end mount plate as shown and described.

DESCRIPTION

FIG. 1 is a rear perspective view of a fluid end mount plate in the environment of a fluid end;

FIG. 2 is a rear perspective view of the fluid end mount plate of FIG. 1;

FIG. 3 is a front perspective view of the fluid end mount plate of FIG. 1;

FIG. 4 is a rear view of the fluid end mount plate of FIG. 1;

FIG. 5 is a front view of the fluid end mount plate of FIG. 1;

FIG. 6 is a first side view of the fluid end mount plate of FIG. 1;

FIG. 7 is a second side view of the fluid end mount plate of FIG. 1;

FIG. 8 is a top view of the fluid end mount plate of FIG. 1; and,

FIG. 9 is a bottom view of the fluid end mount plate of FIG. 1.

The broken, dot-dash lines in each of FIGS. 1-5 define an interior boundary of the claimed design. Neither portions within the broken, dot-dash lines nor the lines themselves form a part of the claimed design. Additionally, any portions shown using dashed lines are for illustrative purposes only and form no part of the claimed design.
